COMBINED TAILLIGHT AND SIDELIGHT UNIT FOR AUTOMOBILES OR THE LIKE

Richard A. Teague, Franklin Village, Mich., assignor to
American Motors Corporation, Kenosha, Wis., a cor-
poration of Maryland

Filed Oct. 18, 1966, Ser. No. 4,323

Term of patent 7 years

(Cl. D48—32)

FIGURE 1 is a perspective view of a combined taillight and sidelight unit for automobiles or the like showing my new design, the broken lines showing a portion of an automobile for illustrative purposes;

FIGURE 2 is an enlarged front elevational view;

FIGURE 3 is a sectional view taken along line 3—3 of FIGURE 2;

FIGURE 4 is a sectional view taken along line 4—4 of FIGURE 2, the broken lines showing a portion of the automobile as in FIGURE 1;

FIGURE 5 is an elevational view taken along line 5—5 of FIGURE 4; and

FIGURE 6 is an enlarged perspective view of the combined taillight and sidelight unit.

The characteristic features of my design reside in the portions shown by means of full lines in the drawings.

I claim:

The ornamental design for a combined taillight and sidelight unit for automobiles or the like, substantially as shown and described.
